United States Patent Office.

GALUSHA MARANVILLE, OF HAMPTON, NEW YORK, ASSIGNOR TO D. A. WILSON AND EBENEZER GOULD, JR.

Letters Patent No. 74,838; dated February 25, 1868.

IMPROVEMENT IN MECHANISM FOR OPERATING STATIONARY MACHINERY.

The Schedule referred to in these Letters Patent and making part of the same.

TO ALL WHOM IT MAY CONCERN:

Be it known that I, GALUSHA MARANVILLE, of Hampton, in the county of Washington, and State of New York, have invented a new and improved Mechanism for Operating Stationary Machinery; and I do hereby declare that the following is a full, clear, and exact description thereof, which will enable others skilled in the art to make and use the same, reference being had to the accompanying drawings, forming part of this specification.

Figure 1 represents a side elevation of my invention.

Figure 2 is a plan or top view of the same.

Figure 3 is a vertical sectional elevation of the same, taken on the plane of the line $x x$, fig. 2.

Similar letters of reference indicate corresponding parts.

This invention relates to a new arrangement of gear-wheels, looms, cranks, and levers, for driving suction-pumps, force-pumps, and other suitable stationary machinery.

The invention consists, first, in the general arrangement of gear-wheels for obtaining the aforesaid object, and also in a new method of converting rotary into oscillating motion.

The machine is so arranged that three different machines can be operated at once by it, it working one oscillating and two rotating shafts. The oscillating-shaft will be especially advantageous for operating one or two suction-pumps, while one of the rotary shafts may drive a chain or bucket-pump, and the other any suitable machinery.

A, in the drawing, represents the frame of my improved apparatus. In the frame A are the bearings for six shafts, B, C, D, E, F, and G. All these shafts are parallel with each other. The shaft B is the driving-shaft, and receives motion from suitable spring-weight, or otherwise. On the shaft B is mounted a gear-wheel, a , which meshes into a pinion, b , on shaft C, thereby revolving the latter. A gear-wheel, c , on the shaft C, meshes into pinions d and e that are mounted on the shafts D and F respectively, as is clearly shown in figs. 1 and 3. A gear-wheel, f , on the shaft D, meshes into a pinion, g , on the shaft E, and thus rotary motion is imparted from the shaft B by means of wheels on the shafts C and D to the shafts E and F. On the shaft E is formed an endless screw, h , which meshes into a toothed wheel, i , which is mounted on a shaft, H, that has its bearings in the frame A at about right angles to the other shafts, as shown in fig. 2. On the shaft H is mounted a pulley, j , from which, by means of a suitable belt, or otherwise, motion may be transmitted to some suitable machinery. On the shaft F is also mounted a pulley, k , or some equivalent device, for imparting motion to a belt, or, if desired, to a chain or bucket-pump, I, as shown. l is a crank, projecting from the shaft F, and m is a longer crank, projecting from the shaft G. The ends of the cranks l and m are connected by means of a rod, n , and thus, when the shaft F revolves, oscillating motion is transferred to the shaft G. On the shaft G is mounted a walking-beam, o , which, when it thus receives oscillating motion, may be used to drive two suction-pumps, J J, or some other suitable machine.

Thus, from the one shaft B, motion can be imparted to three different machines. It is evident that the number of intermediate shafts and gear-wheels may be varied at pleasure, the amount of power and the velocity required, regulating and indicating their number.

I claim as new, and desire to secure by Letters Patent—

1. Transmitting, from one shaft, B, by intermediate gear-wheels and shafts C D E, motion to two revolving shafts, F and H, and to one oscillating-shaft, G, all made and operating substantially as described, so that, from one driving-shaft, three or more various machines may be operated, as set forth.

2. The manner of converting rotary into oscillating motion by connecting a short crank, l on the revolving shaft F, by means of a rod, n , with a long crank, m , on the oscillating-shaft G, substantially as herein shown and described.

The above specification of my invention signed by me, this 6th day of December, 1867.

GALUSHA MARANVILLE.
